(57) **CLAIM**

The ornamental design for a bag with lateral extending members, as shown and described.

DESCRIPTION

FIG. 1 is an isometric view of a bag with lateral extending members showing my new design;

FIG. 2 is a front elevational view thereof;

FIG. 3 is a top plan view, shown without the unclaimed strap and strap hardware, thereof;

FIG. 4 is a bottom plan view thereof;

FIG. 5 is a right elevational view thereof;

FIG. 6 is a left side elevational view thereof;

FIG. 7 is a rear perspective view thereof;

FIG. 8 is a cross sectional view in the direction of the line labeled **8** on FIG. 3

FIG. 9 is a cross sectional view in the direction of the line labeled **9** on FIG. 3; and,

FIG. 10 is a rear elevational view thereof showing my design.

The dashed broken lines show portions of the strap, strap hardware and stitching, and form no part of the claimed design. The zig-zag broken lines shown at the ends of the straps depict symbolic break lines and form no part of the claimed design.
